UNITED STATES PATENT OFFICE.

WILMER G. BUCK, OF FREMONT, NEBRASKA, ASSIGNOR TO CONTINENTAL ENGINEERING CORPORATION, OF OMAHA, NEBRASKA, A CORPORATION OF NEBRASKA.

VALVE-ROTATING DEVICE.

1,414,499.

Specification of Letters Patent. Patented May 2, 1922.

Application filed June 5, 1918. Serial No. 238,275.

To all whom it may concern:

Be it known that I, WILMER G. BUCK, a citizen of the United States, residing at Fremont, in the county of Dodge and State of Nebraska, have invented certain new and useful Improvements in Valve Rotating Devices, of which the following is a specification.

The present invention relates to a means for giving a partial rotative movement to a puppet valve while the said valve is moving in one direction, and to allow it to move it in the other direction with a straight line movement.

The general principle involved in the present application is disclosed in my previous Patents No. 1,183,852, May 23, 1916, valves for gas engines, and No. 1,244,287, October 23, 1917, valves for internal combustion engines.

The objects of the invention are, to provide separate members, each having a clutch surface, which surfaces will come into engagement upon the upward movement of the valve; to impart a rotative movement to one of said members, which movement will be imparted to the other of said members by reason of the clutch engagement; and the other member being connected to the valve stem will impart a rotative movement thereto.

A further object of the invention is to arrange these clutch surfaces as to enable them to be made of a substantial and strong character adapted to withstand the strain of use.

A further object of the invention is to enable the assemblage of the rotating device to the valve without altering in any way the character of the valve stem, utilizing the ordinary valve stem key and slot connection for securing the rotating device to the stem.

A further object of the invention is to generally simplify the construction and to reduce the cost of production.

The invention further consists in the features of construction and combination of parts hereinafter described and claimed.

50 In the drawings:

Figure 1 is a section of a portion of a gas engine with the device of the present invention in operative position;

Figure 2 is an enlarged vertical section 55 through the rotating mechanism;

Figure 3 is a section on line 3—3 of Fig. 2, looking in the direction of the arrows;

Figure 4 is a section on line 4—4 of Fig. 2, looking in the direction of the down-pointing arrows;

Figure 5 is a section on line 4—4 of Fig. 2, looking in the direction of the up-pointing arrows; and

Figure 6 is a view looking on the lower end of the rotating mechanism.

Referring now to the drawings, the invention is shown in conjunction with a gas engine casing 7, which may be of any suitable style and construction. A piston chamber 8 is shown, in which is located the usual piston 9, and from which extends the piston rod 10 that connects to the crank shaft (not shown). A cam shaft 11 is illustrated, carrying suitable cam members 12, which operate against a tappet 13 in the usual manner to raise and lower the valve stem to unseat and seat the valve. Located above the tappet is a valve stem 14 of a puppet valve 15, which valve may be so located as to control either the inlet or exhaust opening. The valve stem 14 is moved up and down by the movements of the tappet and causes the valve member to seat and unseat in the usual way.

It has been found that the length of line 85 of the valve is increased if a partial rotative movement is given to the valve member each time it is operated, whereby it is constantly changing its surface with respect to the surface of the seat 16, and the present invention 90 is directed toward the mechanism for carrying out this rotative action. As explained, the mechanism in general is based on the same principle as that disclosed in my prior Patents Nos. 1,244,287 and 1,183,852 previously referred to, and in the present invention there is employed a bushing 17 formed with spiral slots 18 extending through the walls thereof. This bushing is provided with an upper flanged head 19 formed with a recess 20, the walls of which are engaged by a pin 21 secured in the cylinder 22. This bushing is therefore held against any turning movement.

Traveling within the slots 18 of the bushing are lugs or projections 23 attached to a sleeve 24. On the lower end of this sleeve is a flange 25, and immediately below said flange are a series of clutch teeth 26. Attached to the valve stem is a collar 27, 110

formed with an upwardly extending neck 28. This collar has an elongated recess 29 in its lower face (see Fig. 6), in which lies a pin 30 extending through a hole in the valve stem. It is obvious from an inspection of Fig. 6 that the key lying within the recess 29 forms an interlocking connection between the collar 27 and the valve stem 14. The collar 27 is also formed with a ball-race 21, 10 and above said collar is a ring 32 formed with a ball-race 33. Bearing members 34 are inserted in said race, giving a mounting enabling the collar 27 and the valve stem which is joined thereto to partake easily 15 of a turning movement.

The upper end of the neck 28 is formed with clutch teeth 35, which are complementary to the clutch teeth 26. A locking ring 36 is secured to the neck 28 with a driving fit 20 and acts to retain the ring 32 in position; and secured by a driving fit, or otherwise, to the outer periphery of the ring 32 is a cap 37, which cap is formed with an inwardly extending flange 38 having openings 39 there- 25 in. A spring 40 is employed, which extends between a flange 41 on the bushing 17 and a flange 42 on the cap 37. This spring exerts a pressure tending to hold the valve normally downward and in seated position, as in Fig. 1.

30 In assembling the device, the sleeve 24 is inserted through the top opening 37^a in the cap 37, the lugs 23 passing through the openings 39 in the upper inwardly extending flange 38 of said cap after the sleeve has 35 been pushed through the opening 37^a. When the sleeve has been inserted through the cap, the flange 25 on the lower end of the sleeve will engage with the under side of the flange 38 on the cap 37, thus retaining the 40 cap and sleeve together. The locking ring 36 is then applied to hold the ring 32 and collar 27 together and form the ball-bearing mounting. The ring 36, ring 32 and collar 27 are then inserted upon the valve stem 45 and the cap 37 is driven down onto the ring 32, thus assembling all of the parts together. The spring 40 has been previously positioned, and then upon inserting the pin 30 so 50 that it lies within the recess 29 in the collar 27, the entire appliance is affixed to the valve stem, and such appliance may be removed by merely reversing the steps of the operation above described.

55 When pressure is applied to the lower end of the valve stem, the valve is raised, carrying upward the collar 27, ring 32, ring 36 and cap-piece 37, and acting to start the compression of the spring 40. The teeth of the clutch surfaces 26 and 35 are brought 60 into clutch engagement, so that upon further upward movement, the sleeve 24 is moved upward. This moves the lugs 23 upward, which are joined to said sleeve, and since they rest within the spiral slots 18, it 65 is obvious that the sleeve 24 will be given

a rotative movement upon such upward movement. This rotative movement will be transmitted, through the engagement of the clutch teeth 35 and 36, to the collar 27, and from said collar to the valve stem, and 70 from the valve stem to the valve head or member 15, so that upon such upward movement the valve member will be given a partial rotative movement.

When the cam 12 releases from the lower 75 end of the tappet, the spring 40, which has been compressed by the upward movement of the valve, will act to return the parts to normal position and will exert a downward pressure upon the cap-piece 37, which pressure is transmitted to the ring 32 and the collar 27, and by reason of the connection between the collar and valve stem 14, serves to lower the latter and return the valve member to seated position. Immediately when 80 this downward pressure of the spring is exerted, the clutch surfaces 26 and 35 will be moved out of clutching engagement, since the surface 35 will move with the collar 27 and under the influence of the spring, whereas 85 the surface 26, being attached to the sleeve 24, is not influenced by the spring. This separation of these clutching surfaces will allow the valve stem to return to normal position without any rotative movement, and 90 thus the valve will be rotated only when 95 moving in one direction.

By arranging the clutch members in the manner described, the teeth thereof can be made of a size and character to be strong 100 and durable; and by forming the parts of the rotator device in the manner described, the only means necessary to join the valve stem and said device is the ordinary valve 105 stem key 30, which is common to all valve constructions. The device can, therefore, be applied to the standard valve without any 110 change or modification whatsoever in the latter.

I claim:

1. In a device of the class described, the combination of a reciprocating valve stem having a valve member thereon, a sleeve loosely mounted on the stem, a collar connected to the stem, co-operating clutch surfaces on the adjoining ends of the collar and sleeve, means carried by the collar and engaging said sleeve, said means permitting of a slight separating movement between the aforesaid clutch surfaces, means for imparting an oscillating rotative movement to said sleeve as it is moved up and down, said clutch surfaces engaging upon upward movement of the parts, whereby rotative movement is transmitted from said sleeve 115 through said collar and to the valve stem, a spring exerting a pressure on said collar to separate said clutch surfaces when the valve is moved downward, whereby no rotative movement is imparted to the valve 120 125 130

stem on its downward movement, and said means carried by said collar engaging said sleeve to move it downward after said clutch connection is broken, substantially as described.

2. In a device of the class described, the combination of a reciprocating valve stem having a valve member thereon, a sleeve loosely mounted on the valve stem, means for imparting an oscillating rotative movement to said sleeve as it moves up and down, a member affixed to the valve stem, a lost-motion connection between adjacent end portions of said member and sleeve, clutching surfaces on said member and sleeve adapted to engage while the valve is moving in one direction, means for causing their disengagement when the valve is moving in the opposite direction, and said connection serving to engage and move said sleeve while the parts are moving in said opposite direction, substantially as described.

3. In a device of the class described, the combination of a reciprocating valve stem having a valve member thereon, a sleeve loosely mounted on said stem, a member affixed to the stem, a cap-piece secured to said affixed member and engaging with said sleeve in a manner to permit a slight movement of said sleeve with respect thereto, means for imparting an oscillating rotative movement to said sleeve as it moves up and down, co-operating clutch surfaces on said affixed member and sleeve adapted to engage when the parts are moving in one direction, means causing a disengagement of said clutch surfaces when the parts are moving in the opposite direction, and said cap-piece engaging and moving said sleeve during said movement in said opposite direction, substantially as described.

4. In a device of the class described, the combination of a reciprocating valve stem having a valve member thereon, a sleeve loosely mounted on the stem, a member secured to the stem by a single locking key, a lost-motion connection carried by said member and engageable with the adjacent end portion of said sleeve, means for imparting an oscillating rotative movement to said sleeve as it moves up and down, means for effecting a clutching connection between said sleeve and secured member when the parts are moving in one direction, means acting to break said clutching connection when the parts are moving in the opposite direction, said connection between said sleeve and secured

member constituting means for moving said sleeve subsequent to the release to the clutch engagement, and said key serving as the sole means for connecting all of the parts to the valve stem, substantially as described.

5. In a device of the class described, the combination of a reciprocating valve stem having a valve member thereon, a sleeve loosely mounted on the stem, a member affixed to the stem, a chambered housing adjacent the lower end of the stem forming a connection between said member and sleeve and enabling said sleeve to have a slight amount of movement with respect to the affixed member, co-operating clutch surfaces on said member and sleeve, said surfaces coming into engagement when the parts are moving in one direction, means for causing a separation of said surfaces when the parts are moving in the other direction, and said housing acting as a means for moving said sleeve in said other direction, substantially as described.

6. In a device of the class described, the combination of a reciprocating valve stem having a valve member thereon, a sleeve loosely mounted on said stem, a member affixed to the stem, cooperating clutch surfaces on the adjoining ends of the sleeve and the affixed member adapted to engage while the valve is moving in one direction, means for causing their disengagement when the valve is moving in the opposite direction, and a cap secured to the affixed member on the stem and having a lost-motion connection with the loosely mounted sleeve for positively moving said sleeve when the clutch surfaces are disengaged.

7. In a device of the class described, the combination of a reciprocating valve stem having a valve member thereon, a sleeve loosely mounted on the stem and having at one end thereof a flange, a member affixed to the stem, cooperating clutch surfaces on the adjoining ends of the sleeve and affixed member adapted to engage while the valve is moving in one direction, means for causing their disengagement when the valve is moving in the opposite direction, and a cap secured to the affixed member on the stem and provided with a flanged end for engagement with the loosely mounted sleeve above the flange on the end thereof to permit a relative longitudinal movement between the affixed member and the loosely mounted sleeve when the clutch surfaces are disengaged.

WILMER G. BUCK.
